His Attorney.

UNITED STATES PATENT OFFICE

2,087,207

LAMP-POSITIONING DEVICE

Winterton J. Day, Alplaus, N. Y., assignor to
General Electric Company, a corporation of
New York

Application September 11, 1935, Serial No. 40,064

3 Claims. (Cl. 240—44.25)

My invention relates to lamp-positioning devices and more particularly to lamp-positioning devices for projectors in which the positioning of the lamp with respect to the reflector changes 5 the character of the light beam.

One object of my invention is to provide a mechanism responsive to an energization of the lamp to change the position of the lamp.

Another object of the invention is to provide 10 a mechanism operable to move the lamp through successive predetermined positions in response to successive energizations of the lamp.

For a better understanding of my invention, 15 together with other and further objects there- of, reference is had to the following description, taken in connection with the accompanying drawing, and its scope will be pointed out in the appended claims.

In the accompanying drawing, Fig. 1 is a dia- 20 grammatic illustration of the lamp-positioning mechanism, together with the reflector, lamp and the electrical diagram of connections for the lamp and positioning mechanism; Fig. 2 is a perspective view of the positioning mechanism; 25 Fig. 3 is a side view of the mechanism, partly in section, and Fig. 4 is an enlarged perspective of the positioning cam of the mechanism.

Referring to Fig. 1 in detail, a lamp 10 is 30 illustrated as being in a position behind the focal point 11 of a mirror 12. The lamp is shown in a second position, in dotted lines, having its filament 13 coinciding with the focal point 11 of the mirror 12. Due to the shape of the mirror 12, which is paraboloidal, the beam projected, when 35 the lamp filament is in the illustrated position, behind the focus of the mirror, is a wide beam suitable for flood-lighting great areas at close range. When the lamp is in the dotted position, the beam is narrow and useful for long range 40 work. It is desirable at times to change the projected beam without making the adjustments at the projector, and in accordance with my improved mechanism such change can be made by successively opening and closing a lamp 45 switch 14 at a control station. The mechanism by which this is accomplished may be understood by reference to Figs. 2 and 3 of the drawing.

Fig. 2 illustrates a portion of a projector hous- 50 ing 15 in which the mechanism is mounted. The mechanism comprises a base 16 having a pair of parallel prongs 17 and 18 attached thereto and projecting vertically above said base at one end thereof. A pair of arms 19 and 20 are pivoted 55 on the prongs at 21 and 22 respectively and may

oscillate between the prongs of the U-shaped members 23 and 24 mounted on the arms 19 and 20 respectively and arranged to engage the sides of the vertical prongs 17 and 18, thereby limiting the movement of the arms in either direction. The arms 19 and 20 are fastened to each other by an intermediate member 25 upon which a lamp socket 26 is mounted. The lamp socket may be of any desired structure suitable for the base of the lamp used. In the present illustration it comprises a pair of blocks 27 into which the prongs of the lamp are clamped by means of a thumb screw 28.

The lamp support just described is moved to either of its positions and held there by a cam 15 5 29 provided with cam surfaces 30 and 31, one or the other of which engages a tongue 32 on the cross bar 25. The cam is mounted on a U-shaped rocking member 33 which is pivoted on pins 34 mounted in the prongs 17 and 18. The 10 cam is further provided with a slot 35 having hooked ends 36 and 36' to accommodate an operating pin 37. The operating pin is mounted in the free end of a link 38 of a toggle mechanism including the links 38, 39 and 40. The link 40 is pivoted at one end to a rigid support 41 15 by a pin 42 and supports the core 43 of an operating coil 44 which is pivoted thereto by a pin 45. Link 39 is pivoted to link 40 by a pin 46 and links 38 and 39 are pivoted by means of 20 a pin 47 which slides in a slot 48 of a guide member 49. Springs 50 connected between the rocking member 33 and the lower end of link 38 25 hold the cam 29, together with its support 33, on either side of the pivot pins 34. 30

The core 43 is lowered every time its solenoid or coil 44 is energized. At this same time the links 38, 39 and 40 are lowered. Assuming the mechanism to be in the position illustrated in Figs. 2 and 3, the operating pin 37 hooks into 35 the end 36 of the slot 35 and pulls member 29 and its support 33 about the pivot pins 34. As soon as springs 50 pass the pivot pins they snap the member 29 into its new position. At this instance the cam surface 31 strikes the tongue 32 and moves the lamp support until it is stopped 40 by the stops 23 and 24 engaging the prongs 17 and 18 respectively. 45

When the solenoid 44 is deenergized, the springs 50 raise the entire toggle mechanism, and 50 operating pin 37 slides to the upper end of the slot. It must be noted that the upper surface of the slot 35 is smooth and permits a free movement of the pin 37, while the lower side of the slot has the hooked ends 36 and 36' into which 55

the pin 37 descends and thereby forms a rigid connection between the toggle and the positioning member during the downward movement of the toggle mechanism. Upon a subsequent energization of the coil 44, the above-described operation is repeated and the lamp thereby moved back to its original position.

For the purpose of reducing the current required by the lamp mechanism, during operation 10 of the lamp, an auxiliary coil 51 and lever 52 are provided and arranged to open the circuit to coil 44 and hold it open during the operation of the projector. For this purpose the lever 52 is pivoted at pin 53 and supports an armature 54. 15 When the core 43 descends, it engages the lever 52 and moves the armature 54 into engagement with the core 56 of the auxiliary coil 51 which is energized simultaneously with the lamp 10. A switch 57 connected into the circuit of the coil 20 44, as illustrated in Fig. 1, is opened by the lever 52 through an operating rod 58. As soon as this switch is open the coil 44 becomes deenergized and permits the armature 43 and the toggle mechanism to rise in response to the action of the springs 50.

The circuit for the device is illustrated in Fig. 1. The switch 14 is the main operating switch and when closed, conducts current from any suitable mains 58' to conductors 59 and 60. 30 Current is thereby led to the lamp 10 by conductors 61 and 62, to the auxiliary coil 51 through a resistor 63, and to the operating coil 44 through switch 57. When the switch 14 is, therefore, first closed, the mechanism is operated to change 35 the position of the lamp as above explained. This change may bring the lamp into focus or out of focus depending upon what position it was in before the energization of the coils. If the mechanism is in the position illustrated in Figs. 40 2 and 3, the first energization of the coils will move the lamp into focus with the mirror. As long as the switch 14 remains closed and current flows through the circuits of the auxiliary coil, the operating coil remains deenergized. When 45 the switch is opened, however, the armature 52 is released thereby closing the operating coil circuit, and the operating coil may again be energized at the next closing of the switch 14. When the coil 44 was deenergized the pin 37 moved to 50 the upper end of the slot 35. When the switch 14 is again closed the pin 37 hooks into the end

36' of the slot 35 and pulls down the cam until its cam surface 30 engages the tongue 32 and moves it into the position illustrated in Fig. 2.

For the purpose of manually operating the mechanism, an operating hook 65 is provided. 5 The hook 65 projects through a bushing 66 in the wall of the casing 15 and is provided with a handle 67. The hook is normally raised by a spring 68, but when pulled down it engages the pin 47 on the toggle mechanism. The resulting 10 operation is the equivalent to an energization of the coil 44.

What I claim as new and desire to secure by Letters Patent of the United States is:

1. In a light projector, the combination of a 15 reflector, a lamp, a pivoted support therefor whereby the lamp may be moved to either one of a plurality of predetermined positions with respect to said reflector, a current circuit for said lamp, a switch in said circuit and means responsive to successive closures of said switch and corresponding energizations of said lamp for moving said support to its predetermined positions successively.

2. In a light projector, the combination of a 25 reflector having a focus, a lamp, a circuit therefor and a switch arranged to open and close said circuit, a pivoted support for said lamp arranged to move said lamp into and out of focus with said reflector, and means responsive to successive 30 closures of said switch and corresponding energizations of said lamp for alternately positioning said lamp in and out of focus with said reflector.

3. In a light projector, the combination of a 35 housing, a reflector, a lamp, a lamp-positioning means in said housing, said positioning-means including a support for said lamp operable to several positions, in each of which positions said lamp is held in a predetermined relation to said 40 reflector, a cam operable to move and hold said support in its several positions respectively, a toggle mechanism arranged to engage said cam at points dependent upon the position of said cam, means responsive to energizations of said 45 lamp for operating said toggle, and means projecting through the wall of said housing for manually operating said toggle mechanism independently of said first operating mechanism.

50 WINTERTON J. DAY.
